UNITED STATES PATENT OFFICE.

JAMES G. BEATTIE, JACOB HUETHER, AND JAMES E. MARTIN, OF NEW YORK, N. Y., ASSIGNEES
TO ROBERT GAIR COMPANY, OF NEW YORK, N. Y., A CORPORATION OF NEW YORK.

BOX-COVERING MACHINE.

No. 863,579.

Specification of Letters Patent.

Patented Aug. 20, 1907.

Application filed February 10, 1905. Serial No. 245,084.

To all whom it may concern:

Be it known that we, JAMES G. BEATTIE and JACOB HUETHER, residing at New York, borough of Brooklyn, in the county of Kings and State of New York, and JAMES E. MARTIN, residing at New York, borough of Manhattan, in the county of New York and State of New York, citizens of the United States, have invented certain new and useful Improvements in Box-Covering Machines; and we do hereby declare the following to be a full, clear, and exact description of the invention, such as will enable others skilled in the art to which it appertains to make and use the same.

The invention herein described relates to machines for applying to paper or card-board boxes, and their tops, plain or embossed, glazed or unglazed, paper-covers and affixing the said covers to the bottoms and sides and ends of such boxes and their tops and turning in and affixing the edges of the covers to the inside of the top edges of the box and their tops for the purpose 20 of covering and finishing the said edges.

The object of the invention is, first, to simplify the construction and operation of machines of this character, to render the operative parts readily accessible, and adapt them to perform their several operations by simple 25 direct and generally positive motions in horizontal lines; second, to obviate the liability of the operator being injured while feeding the boxes to the machine; third, to operate the devices which carry the box and hold and present it to the covering mechanism positively by a single cam and retain control of the box and cover both when moving and at rest until the covered box is stripped from the device that holds it on the support and carrier during the covering operations; fourth, to prevent fouling of the tab-folding devices by the offsetting of the glue pressed out by the tab-folders from 35 between the infolded tabs and the ends of the box; fifth, to prevent the sides of the box and cover affixed thereto from bulging or becoming distorted by the pressure of the tab-folders and the end covering rollers; sixth, to 40 eject the box after the covering is completed from the machine at the bottom or below the covering mechanism, and thereby avoid returning the covered box through the covering mechanism to the top of the machine and exposing it to injury by the mechanism, or 45 defacement by the offsetting of any glue that may adhere to the mechanism; seventh, to strip or shed the covered box from the device that holds it on the support and carrier without danger of injuring the same; eighth, to obviate the liability of injuring the edges of the box 50 when turning the edges of the cover over and down and affixing them to the inside of the top edges of the box; ninth, to insure a prompt, quick and jarless return of the box and cover support and carrier to its normal position flush with the feed table; and, finally to insure 55 promptness in the working of the machine, facilitate the

work of the operator and prevent injury to the box and covering and carrying devices by the sudden reversal of their motions and their abrupt stoppage when they return to their normal positions.

The object first mentioned is attained by locating 60 the covering devices, the tab-folding mechanism, the edge turning mechanism, the stripping or shedding mechanism and the ejector in galleries, and arranging the operating mechanism that connects these parts with the driving mechanism in horizontal planes so 65 that the devices for operating these several mechanisms in each gallery are distinct and separate from those which operate the mechanisms in the other galleries, this object being further secured by operating the mechanism in the several galleries from a single shaft 70 geared to the driving shaft.

The second object is attained by arranging the device that holds the box and cover on the support or carrier and move the same downward to the covering mechanism so that the operator can feed the box to 75 the machine by grasping it by the top thereof and avoiding placing the hand under the said device, and hold it thereon until it rests between the said device and the support or carrier, thus obviating the danger arising from the liability of the operator's hand being 80 caught and crushed between the device and support and carrier.

The third object is attained by a loom cam operating upon the device that holds the box and cover on the support and carrier and moves them downward to the 85 covering mechanism, through rack bars and pinions so that the support and carrier is controlled by the cam when moving and also when at rest; the box and its cover being carried by direct acting mechanism they are presented to the successive covering devices at the 90 instant these devices are ready to operate in turning and affixing the different parts of the cover to the box, and their movements are arrested promptly at those points where the motions of the devices are at right angles to the motion of the box and cover and where 95 consequently, if any movement of the box and cover took place they would be injured by these devices.

The fourth object of our invention is attained by arranging the tab-folding devices so that after moving parallel to the ends of the box far enough to tuck or 100 fold in the tabs and press and affix them to the ends of the box, they are swung outward away from the box before they pass the edges of the tucked in tabs and come in contact with the glue squeezed out from between the tabs and the ends of the box, whereby off-setting of the expressed or exuded glue and fouling of the tab-folders are prevented.

The fifth object of our invention is attained by means of vertical plates alined with the side covering devices and extended down below the tab-folders and 110

the end covering devices by means of which the sides of the box are supported and braced when the tab-folders and end covering devices bear against the ends of the box in folding in and affixing the tabs to the ends of the box and turning up and affixing the ends of the cover to the infolded tabs and the ends of the box.

The sixth object of our invention is attained by providing stripping or shedding devices located in the third and lowest gallery and in line with the extreme 10 downward position to which the covered box descends, whereby when it arrives at this position, the strippers are advanced and engage the top edges of the box while the device that holds the box on the support and carrier is withdrawn by the action of the cam and 15 the connecting mechanism and the box is released and left standing on the support and carrier, ready to be ejected from the machine.

The seventh object of our invention is attained by providing an ejector just below the stripping or shedding devices which instantly, after the box is released, 20 and by a quick action, ejects the box from the support and carrier before the latter begins its upward motion to return to its normal position flush with the top of the feed table.

25 The eighth object of our invention is attained by making the edge turning devices movable horizontally to turn the edges of the cover over the top edges of the box and hold them temporarily in that position until by reversing the motion of the support and carrier the 30 edge turners are caused to enter the box and turn the edges of the cover down parallel to the inside surface of the box to which they are affixed by imparting pressure to both sides and ends of the box simultaneously against the resistance of the edge turners within the box, 35 between which and the presser blocks the edges of the cover are affixed to the inside of the box.

The ninth object of our invention is attained by connecting the support and carrier with a piston operating in a cylinder provided with valves so that the 40 reversal of the motion of the support and carrier will be effected by the action of the air compressed in the cylinder by the action of the piston and the downward movement of the support and carrier, whereby the support and carrier is caused to bear upward against the pressure of the device by which it is forced down, 45 is also held stationary when the downward pressure ceases and moved upward when the device is moved upward or lifted from it after the box is stripped off.

The leading objects of our invention and the means 50 of attaining them are set forth but many minor but none the less important and valuable improvements are incorporated in the machine which will be pointed out and explained when the construction and operation of the several parts and their relation and co-ordination are described in detail and in connection with the drawings.

Simplicity of construction by the use of as few and 60 simple mechanical elements as possible to produce the results, directness of connection between the driving mechanism and the operative parts of the machine and as many positive motions as possible, have been our aim in the production of this machine and compared with other machines these results have been obtained without sacrifice of efficiency.

The invention will now be described in connection 65 with the accompanying drawings, in which

Figure 1 is a sectional rear elevation of our newly invented box covering machine. Fig. 2 is a vertical cross section thereof taken on line $x-x$ of Fig. 1. Fig. 3 is a horizontal sectional plan of the machine—the 70 section being taken on line $y-y$ of Fig. 1, showing a plan of the first gallery and the mechanism located therein—this view being drawn on a larger scale than Fig. 1. Fig. 4 is a horizontal sectional plan of the machine showing the second gallery—the section being taken on line $z-z$ of Fig. 1, showing a plan of the mechanism located in the said gallery—this illustration also being drawn on a larger scale than Fig. 1. Fig. 5 is a plan of the third gallery showing the shedding mechanism—drawn on a larger scale than Fig. 1. Fig. 6 represents the cam and the lower part of a slotted bar which is operated by the said cam. Fig. 7 represents on an enlarged scale a vertical section of the air cylinder in which the piston of the support and carrier operates, the valve chambers and the air passage, showing also the valves and valve rods. Fig. 8 represents the edge turners brought together and forming the frame. Fig. 9 represents a box cover. Fig. 10 a box ready for covering. Figs. 11 to 15 represent the various stages of applying the several parts of the 90 cover and affixing them to the box. Figs. 16, 17, 18, 19, 20, 21 and 22 show in detail the mechanism or means for starting and stopping the machine. Figs. 23 and 24 show in detail the stationary and movable jaws and the presser blocks.

The several parts of the machine will be described under appropriate heads and with reference to the accompanying drawings:

Frame of the machine.—This is constructed of side members A A each of which consists of uprights B B 100 and a cross bar C. Each of the side members is preferably an integral casting. They are connected together below the driving mechanism by transverse rods D D and at the top by a plate E.

F G are standards bolted or otherwise fastened to 105 the top E. Standard F is placed at the front side of the top and standard G at about the center.

H is a bracket fastened to the top at the rear side and projected from the same, that has a journal-bearing —a— formed therein and fitted with a cap.

I is a bar bolted to the rear side of the frame that has a pedestal journal-bearing —b— connected with it and which is in vertical alinement with the upper journal-bearing —a—.

A projection J on the front side of the standard F at 115 the top has a rectangular slot —d— in it in line with a similar slot —e— in the top E at the front; the two slots serve as guides for the rack-bar hereafter referred to; and cap plates are fitted over these slots to hold the rack-bar in the slots. Standard F is also provided with 120 journal-bearings, and a shaft —f— is journaled therein and carries two rack-pinions which will be described later.

K is a feed board or table supported between the side frames below the top E and having its front extended 125 outward and hollowed out to partly receive the body of the operator for convenience in feeding the machine. The table has a central square opening —g— large

enough for the covers of the largest boxes to pass through when spread out flat.

Projections $h-h'$ at the top and bottom of the standard, G are slotted and fitted with caps to form 5 guide slots $i-i'$ for the rack-bar that carries the box and cover holder which, as shown in this instance, is a plunger and will hereafter be described more fully. These slots $i-i'$ are in line with a rectangular opening j in the center of the top E. On top of the feed 10 table there are adjustable gages $l-l'$ to guide the operator in properly centering the cover on the box and cover support and carrier.

L M are floors secured to the side frames below the feed table and located and spaced so as to form three 15 galleries O P Q, the first between the feed table and the floor L, the second between the floors L and M and the third below the floor M. The boxes and the covers are carried down through these galleries in succession and presented to the covering mechanism as they descend. 20 These floors L M respectively have circular openings $m-n$ centered with the square opening in the feed table; and the edges of the openings $m-n$ are provided with peripheral ridges $p-q$ respectively, that form tracks for the oscillating rings or turn-tables 25 hereafter described.

Driving mechanism:—S is the driving shaft which is supported horizontally at the rear of the machine in journal-bearings $2-2$ bolted to the side frames. This driving shaft carries at one end a driving pinion 30 3 , a belt wheel 4 , mounted loosely on said shaft, and a balance wheel 5 . The belt wheel is put into connection with the driving shaft by means of a clutch 6 splined on the shaft. The movable member of the clutch is put in and out of gear with the 35 fixed member (not shown) in the hub of the driving wheel by means of a hand lever 7 fulcrumed to the end of the bar 8 .

T is a counter-shaft supported transversely of the side frames, and near the middle line between the front and 40 back thereof, in journal-bearings $r-t$ fastened to the side frames. One end of this counter-shaft carries a spur-wheel 9 that meshes with the driving pinion 3 and the opposite end carries a cam 10 .

A vertical shaft U is journaled in the bracket bearing 45 a and the pedestal bearing b . This vertical shaft carries a bevel wheel 11 that meshes with a bevel wheel 12 on the counter-shaft T. The spur-wheel 9 runs free on the counter-shaft and is driven continuously by the driving-pinion. The 50 counter-shaft is designed to make one revolution during which the box is completely covered and ejected from the machine and the depressing device and box and cover support and carrier are returned to their normal or starting position ready for the feeding of another box 55 and cover to the machine, and then brought to a full stop automatically by mechanism which will now be described:—

A treadle 13 at the front of the machine in position to be controlled by the operator's foot, is fitted to a 60 rocking bar 14 , supported transversely of the frame and that carries an arm 15 fixed thereto at the end next to the spur-wheel 9 . This arm has a projection 16 at its upper end and one side of this projection has a vertical inclined face 17 . The upper 65 end of this arm is in line with a circumferential groove

18 in a sleeve 19 splined on the counter-shaft T outside of the hub 21 of the spur wheel 9 . In the sleeve there is a hole 20 parallel to the shaft extending from end to end of the sleeve. A pin 21 is inserted in the hole 20 . This pin has a reduced end 22 next to the spur wheel and its opposite end is bored out to form a socket 23 in which is inserted a coiled spring 24 . The pin is held in the socket by a stud 25 driven through a slot 26 in the sleeve and by a plate 27 inserted in a dove tailed groove in the end of the sleeve behind the spring 24 and fastened by screws. The part of pin 21 that crosses the groove 18 of the sleeve is notched transversely as at 28 and the side 29 of this notch, which is next to the inclined face 17 of the projection 16 of the arm, is inclined about parallel to the face 17 . The pressure of the spring tends to force the reduced end 22 of pin 21 out of the hole 20 into the inclined holes 30 of the hub of wheel 9 ; the pin 25 which travels in the slot 26 tends to keep pin 21 from 70 revolving and thus keeps slot 28 in an alinement with groove 18 . The web of the spur-wheel is provided with a number of holes 30 which are equally distant from the center of the shaft and in line with the end of the pin 21 . By the rotation of the spur 75 wheel these holes are brought in line with the end of the pin which will enter one or the other of the holes when released and the holes come into line therewith as presently described. At the beginning of the operation of the machine the upper end of the arm lies in the groove 18 , and the inclined face 17 of the projection 16 , bears against the inclined side 29 of the notch 28 and thus holds the pin sheathed in the hole against the pressure of the spring. When the treadle is pressed down the arm is thrown out, 80 thereby releasing the pin, and the spring in the socket forces the pin out of the hole against the web of the spur wheel so that when one of the holes 30 comes in line with the pin it enters the hole and thus couples the spur wheel and sleeve together so that the sleeve 85 and with it the counter-shaft are rotated by the spur wheel. When pressure is released from the treadle the upper end of the arm is thrown forward into the groove. As the spur-wheel approaches the end of one 90 revolution the inclined face 29 of the pin is brought into contact with the inclined face 17 of the projection 16 , by the rotation of the sleeve, and bearing against the same the pin is moved back and the reduced end withdrawn from the hole in the web of the spur-wheel, thus uncoupling the sleeve and stopping the rotation of the counter-shaft at the completion of the rotation of the spur-wheel, and stopping also the operation of the machine. Thus by pressing the treadle the machine is started and is promptly stopped automatically when the counter-shaft completes one revolution.

Box and cover carriers:—These comprise a plunger 34 and a vertically movable table 35 which are located centrally in the machine. The table is arranged to be depressed vertically by the descent of the plunger from its normal position in the opening g in the feed table, down through the galleries to the place where the box is ejected from the machine and is returned to its normal position as soon as the box is ejected. The plunger is shaped to correspond to the box to be 130

covered; in this example it is rectangular and its dimensions, that is, its length and width must be such that it will enter the box to be covered easily; hence, as the machine is adapted or intended to cover boxes 5 of various sizes there must be as many plungers for each machine as the machine is otherwise adapted to cover. The thickness of the plunger is less than the depth of the box and its sides and ends fit squarely against the walls of the box, but not so close as to make it difficult 10 to strip the box off of it after the covering is completed. The plunger is socketed to receive the lower end of a rod —36— to which it is fastened by means of a set-screw. The rod —36— works through the opening —j— in the top E and the guides —i—i'— in the projections —h—h'—. The upper part of the rod is formed 15 or fitted with a rack —37— which meshes with a pinion —38— on the shaft —f—. The vertical motion of the plunger is produced by the cam —10— that operates a slotted bar —39— through which the counter-shaft T is 20 passed, the bar being held between collars —40—41— by which it is guided. The said slotted bar has a head —42— which is bent over at right angles and coupled to a rack-bar —43— that is passed through the guide slots —e—d— in the table and the projection J respectively 25 and meshed with a pinion —44— on the end of the shaft —f— opposite the pinion —38—.

The cam —10— is similar to a loom cam and the construction is such that it gives a rapid upward or return movement to the plunger while the downward movement 30 is timed to harmonize with the movements of other mechanism and in places is entirely arrested to allow the covering devices to perform their several operations in covering the box. The cam face is formed by a flange —45— which runs between an anti-friction, 35 roller —46— mounted on a stud —47— and the rollers —48—49— in the lower ends of the arms —50—51— mounted on a stud fixed to the slotted bar, the upper ends of the arms being connected together by a spiral spring —52—. By this construction both the upward 40 and downward movement of the rack-bar are controlled by the cam in part.

Turning up the sides of the cover and affixing them to the sides of the box:—Underneath the feeding table on opposite sides of the opening —g— midway between the side frames there are adjustable plates —53—53— which are connected with the under side of the feed table by means of set screws passed through slots in the plates and into tapped holes in the feed table. The inner ends of these adjustable plates are curved 50 downward and carry bars —54—54— the ends of which are bifurcated and carry spring bolts having in their inner ends journal bearings for the side-covering rollers —55—55— by which the sides of the cover are turned up against and affixed to the sides of the box. The construction of the roller supporting bars —54—54— and the bearings is not illustrated; nor will any detailed description of them be given at present, as the end covering rollers are supported in the same manner and their construction which is in all respects 60 the same and which is illustrated and will be fully described in connection with the description of the mechanism for turning up the ends of the covers and fastening them to the ends of the box. Over the side covering rollers —55—55— there are fixed plates 65 —56—56— the inner edges of which are curved down-

ward over the rollers and project slightly beyond the faces of the rollers. The function of these plates is to scrape off or remove any glue that may spread over the outer sides of the cover or be squeezed out by the pressure of the rollers and thus prevent such glue from 70 reaching the rollers and offsetting thereon. Below the side covering rollers there are vertical side-supporting plates —57—57— in the same vertical planes with the faces of the rollers and which are held in pendent position by the upper inclined ends —58—58— being 75 connected with bars —54—54—. These plates extend down below the devices that apply the ends of the cover to the ends of the box and within the opening of floor L. The function of these plates will be described hereafter.

Tucking in the projecting ends or tabs of the sides of the cover:—The mechanism for this purpose is located in gallery O and will now be described in connection with Figs. 2 and 3 (Sheets II—III). There are four tab-folders, two for each end of the box and those which 80 are connected with the same operative mechanism on one side are marked —59—59— and those on the opposite side —60—60—. As these tab-folders and the means by which they are operated are precisely alike the description of those on one side and the operative 85 mechanism therefor will be equally applicable to those on the opposite side and the mechanism by which they are operated. The tab-folders consist of metal plates —61—. The ends —62— that bear against the projections are convex vertically so that when they bear 90 against the tabs they will tuck the same in against the ends of the box without liability of tearing the paper. They are of about the same width vertically as the depth of the box; hence, as the machine is intended 95 to cover boxes of different depths these tab-folders 100 must be changeable to correspond to the depth of the boxes which the machine is engaged in covering. The shanks —63— of the folders are bent to a rectangular form so that they will slip into vertical slots —63a— in the heads of the pins —64— to connect them with the 105 said pins. By this mode of connecting the tab-folders with the pins they are held firmly but at the same time they are readily removed when it is necessary to change from one size to another. The pins —64— are inserted in horizontal perforations in turrets —65—. 110 These turrets are connected by means of pivots —66— with slides —67— which have square perforations through them for the square bars —68— on which the slides are mounted and secured by suitable set-screws. The bars —68—68— are passed through oppositely 115 placed head-blocks —69—69— and these head blocks have square studs projecting from their under sides which are inserted in sockets in the slides —70—. The slides are connected with the plate L by dove-tailed projections on their under sides inserted in 120 dove-tailed grooves in the plate so that the slides can move in and out or on radial lines to a limited extent for the purpose of moving the tab-folders against the tabs to tuck them in against and affixing them to the ends of the box. The turrets —65— are connected 125 with the lower ends of the spiral springs —71— coiled around their pivots —66—, the upper ends of said springs being connected with tension regulating nuts —72— on the pivots —66—. These springs are for the purpose of holding the tab-folders in their correct po- 130

sition with relation to the ends of the box and at the same time allow them to be positively swung outward and away from the ends of the box at the proper time. They are held in their operative position by means of 5 the springs —71—, and set-screws —73— passed through the lips —74— projecting downward from the inner edges of the turrets and which bear against the faces of the slides —67—. By means of these set-screws the tab-folders can be adjusted with the greatest 10 nicety so that they will bear with the proper pressure against the tucked in tabs to cause them to become affixed to the ends of the box.

The slides —67— are adjustable on the bars —68— to adapt the tab-folders on each bar to be removed 15 towards and from each other to adjust them in connection with tucking in the folds of the boxes of different lengths. Set screws are provided to fasten the slides to the bars and retain them in the position to which they are adjusted. The pins —64— are also movable 20 in and out of the turrets to adjust the tab-folders to boxes of different widths, and set-screws —75— are provided for fastening the pins when the tab-folders are properly adjusted. The slides —70—70— are provided with studs —76—76— which project down 25 through slots —77—77— in the plate L and are inserted in the outer ends of the links —78—78—. A ring —79— having a ridge —80— on its outer periphery is placed in the opening in the plate L with its ridge resting on the ridge —p— of the plate, on which it 30 oscillates—the ridge —p— serving as a track. This ring is flush with the top and bottom of the plate L and on opposite sides studs —81—81— project from its under side and are inserted in the inner ends of the links —78—78—, the links thus connecting the slides 35 —70—70— with the ring. The ring is also pivotally connected with a forked bar —82— (see Fig. 3), the forked outer end of which embraces the vertical shaft U above the cam —83— the face of which bears against a roller —84— on the fork. The ring is also connected 40 with one end of a spiral spring —85—, the opposite end of which is connected with the under side of the plate L. By means of the cam —83— the ring is turned in the direction of its arrow (see Fig. 3) and the return motion is produced by the spring —85—, an oscillating 45 motion thus being given to the ring. By this motion links —78—78— cause the slides —70—70— to move in and out and thereby give a reciprocating motion to the tab-folders which are thus caused to tuck in the tabs and affix them to the ends of the box.

50 The turrets have rearwardly projecting arms —85^a—85^a— which are provided at the outer ends with pendent eyes —86—. Straps or bridges —87—87— which span the slides —70—70— are riveted or bolted to the plate L; to these straps or bridges square studs 55 —88—88— are fastened and on these studs fixed arms —89—89— are mounted. The outer ends of these arms are provided with swiveled eyes —90—. Rods —91—91— are passed through the eyes —86—90— of the respective arms —85—89— thus connecting each 60 of the turrets and the arms —85— with one of the fixed arms —89—. When the opposite tab-folders are moved towards each other to tuck the tabs in and affix them to the ends of the box the glue squeezed from between the ends of the tucked in tabs and the box is apt to offset on the tab-folders. This is obviated

by swinging them away from the ends of the box at the end of their motion or before they reach the ends of the tabs, and this is accomplished by connecting the turret arms —85^a— with the fixed arms —89—. The rods —91— it will be observed are at obtuse 70 angles to the lines of movement of the tab-folders; hence, when the latter move a certain distance, determined by the set of the arms, the outer ends of the rods bear against the eyes in the ends of the arms —89—89— and by their resistance the turrets are 75 caused to turn on their pivots and thus swing the pins —64— outward and carry the ends —62— of the tab-folders away from the tucked in tabs before they reach the edges thereof and take up the glue.

End covering mechanism.—The mechanism for this 80 purpose is located in gallery O and it comprises the elastic rollers —92—92— sleeved on shafts —93—93— (see Figs. 1 and 3), each of which is journaled in bearings in the ends of bolts —94—94— inserted in the bifurcated ends —95—95— of the bars —96—96— connected with 85 the upturned ends of the adjustable plates —97—97— secured to the plate L by set-screws passed down through slots in the adjustable plates and tapped into plate L. The bolts are secured in the bifurcated ends of the rods by nuts on their outer ends, and spiral springs —98—98— 90 are coiled around the bolts between one side of the fork and the collars —99—99—. These springs hold the bolts in their proper positions but allow them to move back or yield more or less when lateral pressure is applied to the rollers. Over the rollers there are guard plates —95—100— having their edges curved downward slightly and projected a short distance inward beyond the faces of the rollers. The function of these rollers is to catch any glue that may drop from the covers and thus protect the rollers. The edges of the covers, particularly the larger ones, are apt to curl over or down when on the support and the glue may drip therefrom and in the absence of the plates —100— the drippings would fall on the rollers, but these guard plates intercept the glue and it can easily be wiped therefrom, 105 whereas it would be difficult to clean off the rollers. The plates —56—56— perform the same useful and valuable function for the side covering rollers —55—55—. The ends of plates —100—100— are fastened by screws to pillars on the bearer ends of the bolts —94—94—. 110 The end covering rollers and the contrivances for supporting and adjusting them and the plates for catching the surplus glue are the same in all respects in construction as the same or corresponding parts thereof described in connection with the side covering rollers.

Edge turning mechanism.—The mechanism for performing these operations is located in the second gallery P and is shown more particularly by Figs. I, 2 and 4 (Sheets I, II and IV). The mechanism is connected with the floor M. An oscillating ring —101— having a 120 peripheral ridge —102— is placed in the opening —n— of floor M with its ridge resting on the ridge —q— which forms a track on which the ring —101— oscillates. The ring is pivotally connected by means of a stud —103— projecting from its under side with the end of a fork 125 —104— which embraces the vertical shaft U over a cam —105—. The fork carries a roller —106— that bears against the face of the cam. The cam turns the ring in the direction of its arrow (Fig. 4) and its reverse motion is produced by means of the spiral springs —107—107— 130

the ends of which are attached respectively to studs —108—108— on the under side of the ring, and stud —109—109— on the under side of the plate M.

On top of the floor M there are sliding plates —110—5 110— which are opposite one another, and —111—111— which are at right angles to the plates —110—110—. These plates have dovetailed projections on their under sides which are inserted in dovetailed grooves in the floor and they are also provided with studs —112—10 which project through slots —113— in the floor and are pivotally connected with the ends of links —114—, the opposite ends of which are pivotally connected with studs —115— projecting from the under side of the ring —101—.

15 The sliding plates —110— and —111— carry respectively the side and end edge turning devices which will now be described but as these devices are precisely alike in construction and operation the same reference characters will be used for the corresponding parts in each of them. The inner ends of the sliding plates are provided with square sockets —116— (indicated by dotted lines only in Fig. 2) in which are inserted square studs —117— that carry head-blocks —118— in the tops of which are grooves —119— parallel to the sides of the sliding plates. Rectangular slotted plates —120— are placed in these grooves under a transverse plate —121— resting on the sides of the groove and secured by screws —122— passed down through the transverse clamping plate and the slots and screwed 25 into the bottom of the grooves. The inner ends of these plates are passed through slots in the movable jaws —123— (which are thus hung on the side plates), and carry fixed jaws —124—. In the edges of the plates —120— there are pins —125—125— on which rock 30 levers —126—126— are fulcrumed, the lower ends of these rock levers are pivotally connected with lugs —127—127— on the rear sides of the movable jaws —123—, and their upper ends are pivotally connected with the ends of links —128—128— the opposite ends 35 of which are pivoted to the ends of cross-bars —129— on an arm of the bell crank levers —130— fulcrumed on pins —131— in the slots in the sliding plates —120—. The other arms of the bell-crank levers are perforated at the end to receive vertical rods —132— the upper 40 ends of which project through the perforations and are fitted with screw clamps —133—, and the lower ends are pivotally connected with the outer arms of rock levers —134— which are pivoted in sockets in the horizontal projections —135— of standards on the plates 45 —110—111—. The other arms of the said rock levers are pivotally connected with rods —136— which in turn are connected with cranks —137—138—139— pivoted on studs —140— inserted in the plate M. The crank —137— has three arms one of which is pivoted to a rod 50 —141— another with a connecting rod —142— which extends to and is pivotally connected with an arm of the crank —139— and the third arm is pivotally connected with the end of a slotted bar —143—. The vertical shaft U passes through the slot in the outer end 55 of the bar —143—. A roller —144— on the slotted end of this bar bears against the face of a cam —145— on the shaft U; and a spiral spring —146— is connected at one end with the slotted bar and at the other end with a pin or stud in the plate M. The cam —145— 60 has one low point —147— and when this reaches the

roller —144— the spring forces the roller into this hollow and thus moves the bar longitudinally to the left and thereby, through the crank and connecting rods, the rock levers —134— are turned simultaneously, thereby causing the bell-crank levers —130— to move 70 the links —128—128— outward and thereby, through the rock levers —126—126—, cause the movable jaws —123— to move towards the fixed jaws —124—.

The return or backward movement of the movable jaws from the fixed jaws, is effected in the following 75 manner: When the high part of the cam —145— bears against the roller —144— it moves the slotted bar back thereby, through the cranks, rocking the rock-levers —126—126— in a direction the reverse of their arrows, and throwing the rods —136— upward and lifting the 80 clamps away from the arms of the bell-crank levers —130—. The movement of the rock levers —130— is aided and made more prompt by means of spiral springs —148— connected at one end with the rock-levers and at the opposite end with fixed studs in the 85 side frames of the machine. When the arms of the bell-crank levers —130— are released by the upward movement of the rods —132— screw clamps 133, spiral springs —149—149— connected with the plates —120— and the cross bars —129— turn the rock-levers —126—126— and thereby pull the movable jaws back and away 90 from the fixed jaws.

The fixed jaws carry the edge-turning plates —150— by which the edges of the sides and ends of the cover 95 that project above the top edges of the box, are first turned over horizontally or at right angles to the sides and ends of the box and held in that position until, by a further movement, they are bent downward parallel to the sides and ends after which the movable jaws 100 carrying the presser blocks —151— impart simultaneously lateral pressure against the exterior surfaces of the ends and sides in line with the turned in edges and press the sides of the box against the turned down edges of the cover and thus cause the latter to be affixed 105 to the inside surface of the side and end edges of the box. The first movement, viz. that by which the edges are turned over horizontally is produced by the oscillating ring —161— which, when moved in the direction of its arrow by the cam —105— causes the sliding plates —110—111— to move inward thereby carrying the edge turning plates against the upward projecting ends of the cover, above the top edges of the box and causing the edge-turners to turn the edges over horizontally 110 until the said plates come together and form a rectangular frame (Figs. 4 and 8) the length and width of which correspond very nearly to the internal length and width of the box so that it can pass easily down into the box and its sides and ends form the immovable surface against which the edges of the cover will be pressed 115 to cause them to adhere to the sides and ends of the box. The box is now moved upward by the operation of the support and carrier which will be hereafter described, thus causing the frame to enter the box and the bottom edges of the edge turners to turn the edges of the cover 120 downward parallel to the inner surface of the sides and ends and more or less against the same. At this point the hollow or low point of the cam —145— reaches the roller which enters the same and the spring moves the 125 forked bar and through the cranks and connecting rods 130

turn the rock levers —134— and these rock levers through the rods —132— and links —128— turn the rock levers —126— outward and thrust the movable jaws inward and the presser blocks —151— laterally against the outside of the box and press the same and the down-turned edges of the cover against the faces of the frame and thus cause the edges of the cover to be affixed to the inside surface of the box adjacent to the top edges thereof.

10 *Box and cover support and carrier.*—The movable table or support and carrier —35— has the same shape as the plunger —34— and corresponds to the size of the bottom of the box to be covered. It is provided with a socket piece on its under side and is mounted on the upper end of a rod —152— and secured thereto by a set screw. The lower end of this rod is connected with a piston —153— in a vertical cylinder —154—. This cylinder at the bottom is screwed into a base —155— having an air passage —156— and on opposite sides of the cylinder there are valve chambers —157—158— closed by screw caps —159—160— respectively. In valve chamber —157— there is a valve —161— which opens downward and closes against the seat —162—. Above the valve the walls of the chamber are provided with perforations —163—. The valve is connected with a rod —164— passed up through a stuffing box in the screw cap —159—, and through a coiled spring —165— which bears at its lower end against the top of the screw cap and at the upper end against the collar 25 —166— on the rod. The upper end of the valve rod —164— is pivoted to one arm of a lever —167— fulcrumed loosely on a shaft —168— supported in the cross bars C of the side frames of the machine. The other arm of the lever —167— projects upward and its upper 30 end is provided with a roller which is in position to contact with the cams —169—170—171— on a disk —172— mounted on the counter-shaft T. The valve —173— in valve chamber —158— opens upward and closes down against a seat at the bottom of the chamber and it is 35 connected with a rod —174— that passes up through a stuffing box in the screw cap —166—. A spiral spring —175— is coiled around the rod —174— between the valve and the bottom of the screw cap —160—. The valve chamber —158— is also provided with perforations —176—.

The piston —153— is connected with one end of a strap —177— that passes over a pulley —178— and thence down in the guide tube —179— where it is fastened to a counter-weight —180—. The counter-weight slightly overbalances the weight of the support and carrier so that when unresisted the support and carrier will be moved upward by the gravitation of the weight. Hence when the movable table —35—, supporting the cover and the box, is depressed by the action of the plunger —34— the counter-weight resists the depression of the table and this resistance is sufficient to cause the table to bear firmly against the plunger and thus hold the box and cover securely between them. The downward motion of the support and carrier causes the piston to compress the air in the cylinder under the piston. The degree of the compression however, is regulated by the relief valve —173— which, when the pressure becomes so great as to overcome the resistance of the spring —175— opens and permits the air to escape through the perforations —166—. Valve —157—

is opened during one rotation of the counter-shaft T by the action of the cams —169—170—171—. Thus at the beginning of the downward movement of the support and carrier (—35—) the valve —161— is closed and the air in the cylinder is compressed by the descending piston, the degree of compression being regulated by the relief valve —173—; and it remains closed during the descent and ascent of the support and carrier and until the edge turning mechanism turns over and affixes the edges of the box, and the support and carrier again begins to descend at which point cam —169— comes in contact with the roller on the upper arm of lever —167—, connected with the valve rod —164— and, turning the lever down, the valve is opened and the air allowed to escape from under the piston until the support and carrier reaches its lowest point and the strippers come into action to strip the covered box from the plunger when the cam —169— passes and the valve is closed by the spring on its rod. The suction on the piston resists the action of the counter-weight which tends to move the plunger upward quickly and the suction causes the support and carrier to remain nearly or quite stationary at its lowest position while the stripping off of the box and its ejection of the machine takes place. By this time the cam —170— reaches the roller arm on the lever and bearing upon the same opens the valve partly (cam —170— being somewhat lower or having a less throw than cam —169—), whereupon the air entering the valve chamber —157— through the perforations, passes by the valve and thence under the piston and reduces the suction and the counter-weight moves the support and carrier upward slowly.

During its comparatively slow upward movement the plunger moves upward and the strippers move back out of the way of the support and carrier. When the support and carrier reaches a point say just above the end covering rollers —92—92—, or thereabouts and by the time it reaches this point, the cam —170— passes the roller on the arm of the lever and the roller drops upon the lowest point of the cam —171— at its forward end, which abuts against cam —170—, and the valve is thereby closed a little more so that the quantity of air admitted to the cylinder under the piston is lessened and the suction increased, so that the upward movement of the support and carrier is retarded. But, as the cam —171— rises towards its rear end, it gradually increases the opening of the valve and admits more air to the cylinder and the speed of the support and carrier's upward movement increases; but, as the movement is controlled by the suction so long as the pressure of the air under the piston is below that of the atmosphere the gravitation of the counter-weight is resisted and this continues until the support and carrier about reaches its normal position flush with the top of the feed table when the cam —171— passes the roller of the lever and the valve is closed quickly by the action of the spring on the valve rod cutting off the air, whereby the movement of the support and carrier is checked or slowed down and it arrives at its position without shock or jar.

The stripping mechanism.—The strippers —181—182— consist of plates —182— connected with hangers —183—183— opposite one another and below the floor M. The edges of these plates at the bottom have longitudinal rabbets —184—184— thereby forming horizontal shoulders —185— about as wide or approxi-

mately so as the thickness of the top edges of the covered box. The plates —182— are connected with rods —186—186— which are inserted in square slots in the castings —187— fastened to the under side of the floor 5 M. The outer ends of these slides are connected by links —188— with ring —101—. By means of the oscillating motion of the ring which has heretofore been described links —188— move the rods —186—186— inward and the plates —182—182— are caused to move 10 towards each other so that their shoulders —185—185— will be carried over the side edges of the box while still held on the movable table by the plunger. The strippers are caused to move backward by spiral springs —190— connected with the castings —187— at one end 15 and at the other end hooked on fingers —191— projecting from the outer ends of the rods. The plates —182—182— are adjustable on the rods being movable in and out and the plates thereby moved towards and from each other to adapt them to the width of the boxes that 20 are to be covered by the machine. When the plunger and movable table descend far enough to carry the top edges of the box below the shoulders —185— of the strippers these are moved inward until the shoulders project over the edges of the box. At this moment the 25 plunger is moved upward while the box is held down by the shoulders of the strippers bearing on its upper edges and thus the plunger is withdrawn and the box left standing on the table with its edges under the shoulders of the strippers whereby the table or support and 30 carrier is held down against the pressure of the air in the cylinder under the piston, and the box is ready to be ejected from the machine.

Ejecting mechanism.—The ejector consists of a stem —192— having on its end a rubber cushion —193—. 35 The stem is inserted in a sleeve —194— and secured by a set screw which permits it to be moved in and out to adjust it to the different sizes of boxes. The sleeve is inserted in a block —195— which is connected with a hanger —196— by means of a stud —197— passed 40 through a slot in the hanger and fitted with a thumb nut —198— by means of which the block is securely fastened to the hanger and is adapted to be adjusted vertically. The sleeve is connected by means of a pin —199— with the slotted upper end of an arm —200— 45 the lower end of which is fixed to the shaft —168—. An arm —201— also connected with the shaft has at its upper end a roller which bears against the edge of a wheel —202— having a notch —203— in its edge. The arm —201— is also connected with one end of a spiral spring 50 —204— the outer end of which is connected with a transverse plate —205—. The notched wheel —202— is mounted on the counter-shaft T. When the plunger is withdrawn from the box the notch —203— of the wheel —202— arrives in line with the roller on the arm 55 —201— and the spiral spring pulls it into the notch thereby rocking the rod and causing it to drive the rubber cushioned head —193— of the ejector against the side of the box and eject the box from the table and into the chute —206— whence it is delivered to a receiving 60 table.

Details.—As this machine is adapted to cover boxes of any size up to a square or a rectangle that may be described within the rings —79—101— the side and end covering rollers, the tab-folders and the edge turners 65 are adjustable radially towards and away from the cen-

ter of the machine in order to adapt them to perform their operations upon boxes of various sizes. To this end the side covering rollers are connected with the adjustable plates —53—53—, the tab-folders with the adjustable plates —70—70— the end covering rollers with the adjustable plates —97—97—, the edge turners with the adjustable plates —110—111— and the stripping plates with the adjustable rods —186—186— in the castings —188—188—; and the ejector with the sleeve and block —194—195— as these several parts are adapted to be moved nearer or more distant from the center of the mechanism and when they are moved they adjust the mechanism connected with them. 75

The ends of the edge turning plates —150— are formed with jogs —207— and chamfers —208—. When the 80 side and end plates meet to form the rectangular blocks, as shown by Fig. 8, the jogs and chamfers come together and form right-angular flush joints at the corners. On their bottom the jogs are hollowed out as at —209— so that when turning down the edges of the 85 cover the meeting ends of the edges will be brought together evenly, laid down smoothly and thereby sharp corners are given to the edge covers.

The edge-turners —150— and presser-blocks are held in recesses —211—212— in the jaws —124— and movable jaws —123— by flat springs —213—214— attached at their upper ends to the face sides of the respective jaws their free ends extending down over the recesses with more or less of a curve inward as shown by Fig. 23. The rear side —215— of the fixed jaw —124— is shorter 95 than the rear side —216— of the movable jaw —123—. The holding springs —213— of the fixed jaws are plate-springs and the edge turners —150— are held in the recesses by the springs pressing them against the vertical sides of the recesses. There are two of the springs 100 —214— for each movable jaw, on each side of the jaw plate —120— and their lower ends are inserted in sockets —217— in the horizontal right-angular extension —218— of the presser block, and the springs hold the presser blocks by pressing them against the vertical 105 rear side of the recess. Thus both the edge turners and the presser blocks not being positively held in the jaws they can be easily and quickly removed and replaced by others when changing from the covering of boxes of one size to another larger or smaller. The faces —219— 110 of the presser blocks are covered with rubber to cushion them and produce an elastic pressure against the sides and ends of the box when clamping them against the edge turners to affix the inturned edges of the cover to the box. The faces of the presser blocks are below the 115 ends of the rear sides of the fixed jaw, so that when moved against the box the sides and ends of the latter will be clamped between the cushioned faces of the presser blocks and the sides of the edge turners.

The head of the ejector is connected with the stem 120 —192— by a joint —220— so that it will turn upward out of the way of the support and carrier when the latter strikes it underneath in moving upward to regain its normal position after the box is ejected.

The piston —153— is provided with a leather packing —221— to prevent the air passing around it when moving up and down in the cylinder.

Cam —171— is adjustable at both sides by means of set-screws —222—223— for the purpose of increasing or lessening its throw and thereby the extent of the open- 130

ing of the valve can be regulated to admit the proper quantity of air to control the movement of the support and carrier and also the time of its cutting off to bring the support and carrier to a stop with the least possible 5 shock or jar.

The several parts of the machine having been now described and their operation in performing their several functions explained, the coordinate actions of the several parts and the general operation of the machine 10 in covering a box will now be described.

When the machine is ready for starting, the low point —*w*— of the cam —10— is in contact with the roller —46— as shown by Fig. 6. The operator places a cover —224— (Sheet VII) on the table —35— and centers it 15 there by means of the gages *ll* so that the bottom part within the dotted lines, which covers the bottom of the box lies on the table and the side parts —225— and end parts —226— outside the dotted lines that cover the sides and ends of the box and the tabs or projections 20 —227— that are tucked in and folded against the ends of the box project outside the edges of the table. The operator next places the uncovered box —228— on the plunger —34— grasping it by one corner at the top and holds it thereon while the plunger moves down to the 25 support and carrier. This can be done without putting the hand under the plunger because the plunger is made shallower than the box and the edges of the latter project above the top of the plunger the latter does not prevent grasping of the box by its top edge or edges.

30 The treadle is now pressed down whereby the pin —21— is released and, entering one of the holes in the spur-wheels couples the sleeve to the counter-shaft and starts the cam —10—.

From *w* to *w'* the rise of the cam —10— is abrupt and 35 the plunger is moved down rapidly to the table and support —35— and the box is carried by it and its bottom pressed down on the cover on the table where it is held between the plunger and the table during its subsequent movement. The cam continuing to rotate 40 passes the roller from the point *w'* to *w* thereby moving the plunger down and depressing the table, and the box and cover are carried down between the side covering rollers —55—55— which turn up and affix the sides —225—225— of the cover to the sides of the box as 45 shown by Fig. 11. The plunger and table continue their downward movement and the ends of the cover are brought in line with the tab-folders —59—59—60—60—.

From *w* to *w'* there is a dead part of the cam and the 50 downward movement of the plunger and table is arrested while the tab-folders move laterally against the tabs or projections —227— and tuck them in against the ends of the box and affix them thereto. To accomplish this the tab-folders are simultaneously moved horizontally inward by the cam —83— on the vertical shaft U 55 moving the fork —82— thereby turning the ring —79— which causes the links —78—78— to move the slides —70—70— inward. The tab-folders bear against the tabs or projections —227— and tuck or fold them inward and affix them to the ends of the box as shown by 60 Fig. 12.

From *w* to *w'* the face of the cam rises and in passing from the former to the latter point the plunger moves the table or support and carrier down between the end covering-rollers —92—92— which turn up and affix the 65 ends —226— of the covers to the ends of the box as

shown by Fig. 13. The tucking-in of the projections or tabs and turning up of the ends of the covers and the affixing of these parts to the ends of the box cause considerable pressure against the ends of the box and this has a tendency to bulge the sides and cause the newly 70 affixed sides of the cover to separate therefrom. This is prevented by the vertical plates —57—57— which support the sides of the cover while pressure is exerted against the ends.

From *w'* to *w* the face of the cam rises and while this 75 part is passing the roller the plunger and the table are moved down to the edge turners —150— and when the top edges of the box are at or just below the bottom edges of the edge turners the point *w* of the cam —10— arrives at the roller —46—.

From *w* to *w'* is a dead part of the cam and the movement of the plunger is again arrested while the edges —229— of the cover project above the edges of the box and extend above the bottom edges of the edge-turners and parallel thereto. When this position is reached the cam —105— on shaft U through the connecting rod or bar turns the ring in the direction of its arrow, thereby through the links —114— moving the sliding plates —110—111— inward and by means of the connecting links the edge-turners 85 are carried inward against the edges of the cover and turn them over the top edges of the box to a horizontal position where they are held by the edge-turners as shown by Fig. 14. By this movement also the edge turners are brought together end to end 90 and form the rectangular side supporting frame the dimensions of which, that is to say its length and width are slightly less than the internal length and width of the box so that the frame can enter the box when the latter is raised upward. The position of 100 this frame with respect to the box is indicated by dotted lines Fig. 4. This action of the edge turners takes place while the cam is moving past the rollers —46— or from *w* to *w'*, and as soon as the edge turners pass the edges of the box and their ends meet and 105 form the rectangular side supporting frame the hollow or low point of the cam from *w* to *w'* passes to the roller —46— and the under side of the cam flange —45— bearing down on the rollers —48—49— pull the slotted bar downward to the extent of the depression in the cam, between *w* and *w'*, thereby 110 moving the plunger up to the extent of the down-throw of the cam. At the same time the compressed air in the cylinder under the piston exerts a lifting force on the piston that causes the table to move upward simultaneously with the plunger so that the relative positions of the plunger and table remain the same. Furthermore the action of the compressed air being more prompt, quicker and certain than the action of the cam, the plunger is lifted or moved upward by the pressure of the table beneath resulting from the combined force of the compressed air and the counter-weight.

The upward motion of the table being for the purpose of bringing about the turning down of the edges 115 of the cover inside of the box preparatory to affixing them to the inside surfaces of the sides and ends, it is necessary that it should be effected with the greatest promptness in order to keep time with the following movements of the machine. This is accomplished 120

by the use of compressed air to compensate for the delay or slowness of the action of the cam and counter-weight arising from friction, inertia, lost motion &c. When this upward movement takes place the sides 5 and ends of the box are coincident with a vertical line between the edge turners and the presser blocks —151—; hence by this movement the top edges of the box are pushed up between the edge turners and the side presser blocks, and the bottoms of the edge turners 10 bear upon the horizontal projecting edges of the cover and turn them down parallel to the sides and ends of the box and inside of the same. At this point the hollow or low point —147— of the cam —145— on the vertical shaft U arrives at the roller and the 15 spring pulls the roller into the same, whereby the slotted bar, acting through the connecting rods —136— cranks —138— rock levers —134— vertical rods —132— bell-crank levers —130— and links —128—, throws the movable jaws inward thereby carrying the presser 20 blocks —151— against the exterior of the sides and ends of the box near the top and clamping the said sides and ends and turned in edges of the cover against the faces of the edge turners forming the rectangular side supporting frame, thereby affixing the turned 25 in edges to the inside surfaces of the sides and ends of the box. When this is accomplished the roller passes out of the hollow —147— of the cam and the cam acting against the roller —144— on the slotted bar moves the bar back, thereby reversing the above 30 motions and throwing the movable jaws with the presser blocks backward and away from the sides of the box. This backward motion of the mechanism is facilitated and made more prompt by the spiral springs —148— which make up for lost motion &c., 35 in the connecting rods and the mechanism by which they are operated and other causes that retard the motion of the mechanism, it being necessary, on account of the downward motion of the plunger, which takes place at this time, that the box should be 40 released from the edge turners and presser blocks as quickly and promptly as possible.

With the affixing of the edges inside of the box the covering of the box is completed and it only remains to strip the box from the plunger and eject it from the 45 machine.

From the point w^6 the cam face rises abruptly and when this point passes the roller the plunger again descends and depresses the table, carrying the box down until the top edges thereof are just below the 50 shoulders —185— of the strippers —181—, whereupon these strippers are moved towards the center of the machine until the shoulders project over the tops of the side edges of the box; this occurs about the time the highest point of the cam at w^7 reaches the roller —46— 55 when the plunger is at its lowest position. The strippers now move in until the shoulders are immediately over the top edges of the box whereupon the highest point of the cam passes the roller —46— and the low part from w^7 to w bears against the roller and the plunger moves upward, and as the edges of the box are caught under the shoulders of the strippers the plunger 60 is withdrawn from the box and returns to its normal position above the feed table of the machine while the box remains on the top of the table. At the same moment the notch —203— in the wheel —202— reaches

the end of the arm and the spring —204— pulls the arm over thereby throwing the cushioned head —192— of the ejector against the end of the box and ejects the box from the table into the chute —206— which delivers it to a receiving table (not shown).

When the plunger began its upward movement and the box was stripped off, the high part of the cam —105— passed the roller in the fork —104— and thereupon the springs —107— reacted and turned the ring —101— the reverse of its arrow, whereby through the 75 link connections the sliding plates —110—111— were caused to move back and carry the edge turners to their normal position out of the way of the ascending plunger; also causing the strippers to move back to their normal position. The support and carrier being 80 at this time at its lowest point and the piston at the bottom of the air cylinder the valve —161— is closed so that the suction opposes the counter-weight and the support and carrier remains stationary until the box is stripped from the plunger and ejected, and the plunger has moved upward more or less on its return to its normal position. At this stage cam —170— reaches the lever, and valve —161— is opened partly permitting the air to enter the cylinder under the piston and by reducing the suction allowing the counter-weight 85 to move the support upward but not so rapidly as to overtake the plunger nor before the strippers are moved back out of its way. In its upward course it strikes against the ejector but the latter having a jointed stem swings upward out of its way and when it has passed 90 drops down again to its normal horizontal position. When the support and carrier reaches the level of the end covering rollers, or say about 2/3 of its upward or return travel cam —170— passes the roller on the arm of the lever and the roller drops to the forward low side 100 of the cam —171— and the opening of the valve being thereby reduced the air passing into the cylinder is partly cut off and the suction being increased, the movement of the support and carrier is checked or slowed down. But as the cam rises toward its rear side the 105 valve is gradually opened wider and the movement of the support and carrier is correspondingly accelerated, but continues under the control of the valve so that it arrives at its normal position without shock or jar and at the same moment cam —171— passes the roller and 110 the valve is closed by the spring on the valve rod cutting off the entrance of air whereby the support and carrier is cushioned by the suction of the air against the piston. At or about the time of the arrival of the support and carrier at its normal position, the inclined 115 face of the pin —21— comes in contact with the inclined face of the treadle arm and the pin being drawn back the sleeve is uncoupled from the spur wheel and the operation of the machine thereby stopped.

The blank covers are provided with glue previous to 120 putting them in the machine for covering the box. Where a tight cover is to be placed on the box the entire inside surface of the cover is coated with glue; but where a loose cover is to be put on the box only the edges of the sides, ends and tabs are provided with the 125 glue.

While the above description of the machine is a preferred one it can be largely departed from and modifications may be made to the machine, and we do not 130 restrict ourselves to the exact construction combina-

tion and arrangements of parts shown, but reserve to ourselves all the equivalents thereof that may come or properly be included in the claims following this specification. As for instance in the specification 5 shown, the box carrier is operated by means of a piston in connection with the valve, etc. This same result can and may be obtained by other mechanism.

We claim:

1. In box covering machines a feed table having a central opening therein, a series of floors with galleries between and having openings therein in line with the opening in the feed table, a reciprocating plunger that, during its downward movement passes through the opening in the feed table the galleries and the openings in the floors, 10 a reciprocating box and cover support which is depressed by and coacts with the plunger to hold and carry the box and cover devices in the successive galleries that affix the several parts of the cover to the box, devices that strip the box from the plunger after the cover is affixed, and 15 means by which the devices that strip the box from the plunger are moved over the top edges of the box and hold the support and box when the plunger is moved upward to return it to its normal position above the feed table, substantially as specified.
2. In box covering machines the combination of a vertically reciprocating plunger, a depressible box and cover support that coacts with the plunger to hold and carry the box and cover, a feed table having a central opening therein, a floor situated below the feed table having an 20 opening therein, side covering rolls, yielding bearings for said rolls, bars, adjustable plates to which said bars are connected fastened to the under side of the feed table, tab tuckers, slides dove tailed in the floor below the feed table, connections between the tab tuckers and the slides, 25 an oscillating ring in the opening in the floor below the feed table, means for oscillating said ring and end covering rolls, bars having forked ends, bearings for said end covering rolls mounted in the forked ends of the bars and adjustable plates fastened to the floor on opposite sides 30 of the opening therein to which the said bars are connected, substantially as specified.
3. In a box covering machine a feed table having a central opening therein, a floor under the feed table provided with a circular opening having a ridge on the periphery 45 thereof, an oscillating ring resting on said ridge, means for oscillating the said ring, a vertically movable plunger, a depressible box and cover support that coacts with the plunger to carry the box and cover to the covering mechanisms, side covering rolls situated between the feed table 50 and the said floor on opposite sides of the opening in the feed table, bearings for said side covering rolls, adjustable plates to which said bearings are connected, fastened to the under side of the feed table, pairs of reciprocating tab tuckers located below the side covering rolls on opposite 55 sides of the path of movement of the plunger and support through the feed table and floors, the tuckers of each pair placed opposite each other on the same transverse line parallel to the shorter sides of the plunger, intermediate mechanism that connects the tab tuckers with the oscillating ring and by which when the ring is oscillated in one direction the tab tuckers are caused to move inward to 60 tuck the tabs of the cover against and affix them to the ends of the box, substantially as specified.
4. In box covering machines tab tuckers for tucking the tabs of the box in against and affixing them to the ends of the box consisting of fixed plates having right angular bent shanks, adjustable pins having heads provided with rectangular slots to receive the shanks of the plates, turrets provided with perforations to receive said pins, 65 head blocks to which said turrets are pivoted, spiral springs connected with the head blocks and turrets and provided with tension regulating devices for regulating the pressure of the tab tuckers against the ends of the box, stops on the turrets that bear against the head blocks to limit the inward swing of the tab tuckers, bars mounted in head blocks, a floor having a central opening therein on which the said head-blocks are supported; sliding plates 70 on opposite sides of the opening in the floor on which the
- bars are mounted and that have dove-tailed connections with the first floor below the feed table each of said bars carrying the adjustable head blocks to which the turrets are pivoted and means for reciprocating the slides and causing the pairs of tab tuckers to move towards each other and tuck in and affix the tabs to the ends of the box and then move back from the box, substantially as specified. 80
5. In box covering machines a feed table and a floor below the same, having central openings therein; horizontally reciprocating adjustable tab tuckers connected with suitable supports, slides to which said supports are attached having dove-tailed connections with the first floor below the feed table and on opposite sides of the opening in the floor, an oscillating ring in the opening in said floor, links pivotally connected with the dove-tailed connections of the slides and the ring, a spring connected at one end 85 with the oscillating ring and at the opposite end with the first floor below the feed table which moves the links in one direction, a fork having its end provided with a roller, a vertical shaft in engagement with said fork connected with the driving mechanism and its opposite end pivotally connected with the oscillating ring, and a cam on the vertical shaft by which the fork is moved and caused to oscillate the ring in the opposite direction to move the slides inward and cause the tab tuckers to tuck in the tabs and affix them to the ends of the box, substantially as specified. 90
6. In box covering machines adjustable tab tuckers connected with spring controlled turrets, adjustable head blocks, bars on which said head blocks are mounted connected with supports, reciprocating slides that carry said supports, arms connected with said turrets provided with swiveled eyes, fixed standard provided with swiveled eyes rigid arms on said fixed standard and rods that connect the eyes on the turret arms with the eyes on the rigid arms at a sharp angle to the line of the movement of the tab tuckers, whereby when the tab tuckers are moved forward to tuck in and affix the tabs to the ends of the box the resistance to the movement of the rods by the eyes in the fixed arms cause the turrets to turn and swing the tab tuckers away from the ends of the box before they pass 100 the ends of the tabs, substantially as specified. 105
7. In box covering machines the combination of means for depressing and carrying the box and cover and presenting them to the covering mechanism, tab tuckers for tucking in and affixing the tabs to the ends of the box 110 as the box and cover are passed between the same, end covering rollers situated below the tab tuckers and vertical supports extending down between the tab tuckers and the end covering rolls at right angles to the latter to support the sides of the box against the pressure of the tab 115 tuckers and the end covering rolls, substantially as specified. 120
8. In box covering machines the combination of a feed table having a central opening therein, a depressible support for the box and cover, means for holding the box and cover in their proper relative positions on the support and depressing the same to carry and present the box and cover to the covering mechanism, means for imparting motion to the means for depressing the box and cover support and carrier and means for reversing the motion of the support and carrier to carry the box and cover to the edge turning mechanism to turn the edges of the cover down parallel to the inside surface of the box, substantially as specified. 125
9. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 130
10. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 135
11. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 140
12. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 145
13. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 150
14. In a box covering machine the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked 155

- in tabs or projections of the sides of the cover, means for turning the vertically projecting edges of the sides and ends of the cover over the top edges of the box and holding them in that position temporarily, means for arresting the downward motion of the support and carrier when the edges of the cover are in line with the means for turning the edges of the cover horizontally over the top edges of the box, and means for moving the box and cover support and carrier upward and thus cause the means by which the edges of the cover are turned over horizontally to turn the said edges downward inside of the box parallel to the inside surfaces of the sides and ends of the box, substantially as specified. 85
10. In box covering machines means for turning up and affixing the sides of the cover to the sides of the box and for tucking the tabs against the ends of the box and fastening them thereto, means for turning up and affixing the ends of the cover to the ends of the box, means for turning the edges of the cover over the top edges of the sides and ends and turning the side edges down parallel to the inside of the sides and ends of the box, a plunger, a depressible box and cover support that coacts with the plunger to hold and carry the box and cover, means for moving the plunger and support downward in a vertical path, means for arresting its motion when the box and cover arrive at the tab tuckers, means for moving it downward after the tabs are tucked in and pass the end covering means, means for arresting its motion when the box and cover reach the edge turning mechanism, means for moving it up after the edges are turned horizontally over the top edges of the box and the edge turners pass within the line of the sides and ends of the box to cause the edge turners to turn the edges of the cover downward, means for arresting its motion when the edges are parallel to the sides and ends of the box, means for clamping the sides of the box and the turned down edges of the cover against the edge turning means, means for arresting the motion of the plunger while the clamping mechanism is moving against the sides of the box, and means for moving the plunger and the support with the covered box downward, strippers for stripping the covered box from the plunger, means for moving the same over the edges of the box when they pass below the same and means for moving the plunger upward out of the box when the strippers engage the edges thereof and hold the same on the support when the plunger moves upward, substantially as specified. 90
11. In box-covering machines the combination of a vertically movable plunger, a feed table, floors below the feed table, a depressible box and cover support that coacts with the plunger to hold the box and cover in their proper relative positions and to carry and present the same to the respective covering devices, adjustable plates, jaws connected with said adjustable plates, edge turners connected with and projecting below the jaws, supports for the adjustable plates connected with the second floor below the feed table by dovetailed connections, means for arresting the movement of the plunger when the edges of the cover pass below the jaws and are in the plane of the edge turners, and means for reciprocally moving the plates to carry the jaws horizontally towards each other to cause them to carry the edge turners against the edges of the cover and turn them over the edges of the box horizontally and to bring the ends of the edge turners together inside of the sides and ends of the box to form a rectangular frame, the bottom edges of which hold the edges in their turned over position, substantially as specified. 100
12. In box covering machines the combination of a vertical plunger, a feed table, floors below the feed table, a depressible box and cover support that coacts with the plunger to hold the box and cover in their proper relative positions and to carry and present the same to the respective covering mechanisms, slideable supports on the second floor below the feed table, movable jaws connected with said supports, and edge turners connected with the jaws that project below the same, means for arresting the movement of the plunger and support when the edges of the cover that project above the top edges of the box pass below the jaws and in the plane of the edge turners, means for moving the jaws horizontally towards each other to cause them to carry the edge turners against the edges of the cover and turn them over the edges of the box horizontally and to bring the ends of the edge turners together inside of the sides and ends of the box to form a rectangular frame, the bottom edges of which hold the edges in their turned over position, substantially as specified. 105
13. In box covering machines the combination of a feed table, floors below the feed table edge turners, adjustable slotted plates, jaws that carry the edge turners connected with said adjustable slotted plates, radially slideable plates having dove-tailed connections with the second floor below the feed table, head blocks provided with grooves connected with the radially slideable plates, clamping plates for holding the adjustable sliding plates in the grooves in the head blocks, an oscillating ring in the opening in the second floor below the feed table, pivoted links that connect the slideable plates with the oscillating ring, a spring that connects said oscillating ring with the second floor below the feed table, a fork provided with a roller pivoted at one end to the oscillating ring, a vertical shaft passed through the fork, a cam mounted on said shaft and operating against the roller on the fork whereby when the fork is moved by the cam the ring is oscillated and through the links the plates are moved inward and the edge turners moved against the edges of the cover to turn the same horizontally over the edges of the box, and when the high part of the cam passes the roller the spring moves the slides outward and draws the edge turners back and out of the path of movement of the plunger and support, substantially as specified. 110
14. In a box covering machine the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking in the tabs or projecting ends of the sides of the cover against and affixing them to the ends of the box, means for turning up and affixing the ends of the cover to the ends of the box and the tucked in tabs or projections of the sides of the box, means for turning the vertically projecting edges of the sides and ends of the cover over the top edges of the box and holding them in that position temporarily, means for arresting the downward motion of the support and carrier when the edges of the cover are in line with the means for turning the edges of the cover horizontally over the top edges of the box, means for moving the box and cover support and carrier upward and thus cause the means by which the edges of the cover are turned over horizontally to turn the same edges downward inside of the box parallel to the inside surfaces of the sides and ends of the box, and means moving horizontally against the exterior surfaces of the sides and ends of the box to clamp the same and the turned down edges of the cover against the means by which the edges are turned down inside of the box to affix the said edges to the inside surfaces of the sides and ends of the box, substantially as specified. 115
15. In box covering machines the combination of a depressible support and carrier for the box and cover, means for depressing the same to carry the box and cover to the covering mechanisms, means for imparting a vertical motion to the means by which the box and cover support and carrier is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 120
16. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 125
17. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 130
18. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 135
19. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 140
20. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 145
21. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 150
22. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 155
23. In box covering machines the combination of a depressible support and carrier for the box and cover, means for depressing the same to carry the box and cover to the covering mechanisms, means for imparting a vertical motion to the means by which the box and cover support is depressed, means by which the depressible support and carrier is caused to yieldingly resist the motion of the means by which it is depressed for the purpose of holding the box and cover in their proper relative positions, means for turning up and affixing the sides of the cover to the sides of the box, means for tucking the tabs or projecting ends of the sides of the cover against and affixing them to the ends of the box, means for turning up 160

- and affixing the ends of the cover to the ends of the box and the tucked in tabs or projections, means for turning the vertically projecting edges of the sides and ends of the cover horizontally over the top edges of the box and holding them in that position temporarily, means for arresting the downward motion of the support and carrier when the top edges of the cover are in line with the means for turning the edges of the cover horizontally over the top edges of the box, means for moving the box and cover support and carrier upward and thus cause the means by which the edges of the cover are turned over horizontally to turn the said edges downward inside of the box parallel to the inside surfaces of the sides and ends of the box, means for imparting pressure to all sides of the box simultaneously to clamp the sides and ends of the box and the inturned edges of the cover against the means by which the edges are turned down to cause the inturned edges to be affixed to the inside surfaces of the sides and ends of the box, substantially as specified.
20. 16. In box covering machines the combination of a feed table having a central opening therein, a depressible support and carrier for the box and cover, means for depressing the same to carry the box and cover and present the same to the covering mechanisms, means for imparting a vertical motion to the means by which the box and cover support and carrier is depressed, means by which the depressible support and carrier is caused to yieldingly resist the motion of the means by which it is depressed for the purpose of holding the box and cover in their proper relative positions, means for turning up and fastening the sides of the cover to the sides of the box, means for tucking in the tabs or projections of the sides of the box against and affixing them to the ends of the box, means for turning up and affixing the ends of the cover to the ends of the box and the tucked in tabs or projections, means for turning the vertically projecting edges of the cover horizontally over the top edges of the box and holding them in that position temporarily, means for arresting the downward motion of the box and cover support and carrier when the edges of the cover are in line with the means for turning the edges of the cover horizontally over the top edges of the box, means for moving the box and cover support and carrier upward to cause the edge turning means to turn the edges down parallel to the inside surfaces of the sides and ends of the boxes, means for imparting pressure to all sides of the box simultaneously to clamp the sides and ends of the box and the inturned edges of the cover against the means by which the edges are turned down to cause the inturned edges to be affixed to the inside surfaces of the sides and ends of the box, substantially as specified.
17. In box covering machines the combination of edge turners, jaws for carrying the same, adjustable slotted plates connected with the jaws carrying the edge turners, 55 head blocks, grooves in the head blocks in which said slotted plates are inserted, clamping plates for holding the slotted plates in the grooves, a floor supported in the frame of the machine said floor having radial slots in line with the grooves in the head blocks and a central opening, slides that carry the head blocks having dove tailed connections with the grooves in said floor, an oscillating ring in said floor plates pivotally connected with the oscillating ring and the sliding plates, movable jaws hung on the slotted plate to which the jaws that carry the edge turners are fastened, clamps connected with the movable jaws, and means for moving said jaws to carry the clamps against the sides and ends of the box after the edges of the cover have been turned down inside the box to clamp the sides and ends of the interposed edges of the cover against the edge turners, substantially as specified.
18. In box covering machines, the combination of a feed table, floors below the feed table edge turners, jaws for carrying the same, adjustable slotted plates connected with the jaws which carry the edge turners, head blocks 75 provided with grooves in which said slotted plates are inserted and held, grooves in the second floor below the feed table, slides that carry said head-blocks, a dove-tailed connection between the slides that carry said head-blocks and the grooves in the floor said floor having radial slots 80 in line with the grooves and a central opening, an oscillat-
- ing ring in the opening, pivots on the underside of the oscillating ring, pivoted links that connect the slidable plates with the oscillating ring through the slots in the floor and to pivots projecting from the underside of the oscillating ring whereby when the ring is oscillated the slides by means of the links are caused to turn the movable jaws hung on the slotted plate to which the jaws that carry the edge turners are fastened, clamps connected with the movable jaws, and means for moving said jaws to carry the clamps against the sides and ends of the box 90 after the edges of the cover have been turned down inside the box to clamp the sides and ends and interposed edges of the cover against the edge turners, substantially as specified.
19. In box covering machines means for turning up and affixing the sides of the cover to the sides of the box, means for tucking in the tabs and affixing them to the ends of the box, means for turning up and affixing the ends of the cover to the ends of the box and the tabs, means for turning the sides of the cover over and down inside the 100 box and affixing them to the sides and ends thereof, means for supporting the box and cover, means for depressing said support with the box and cover and carry and present them to the side and end covering means the tab tuckers and the edge turners, means for arresting the depressing and supporting means when the box is between the tab tuckers, means for arresting the motion of the depressing and supporting means when the edges of the turned up cover are in line with the edge turning means, means for moving the edge turners inward to turn the edges horizontally over the top edges of the box and to bring the edge turners together within the line of the sides and ends of the box, means for moving the depressing and supporting means upward to cause the edge turners to turn the edges of the cover down inside the box and parallel 110 to the sides and ends thereof, means for arresting the motion of the depressing and supporting means when the edges are turned down, means for clamping the sides and ends of the box and the inturned edges of the cover against the sides of the edge turners to affix the turned down edges to the sides and ends of the box, means for moving the clamps back after the edges are affixed, means for moving and depressing the supporting means down after the clamps are drawn back, means for stripping the covered box from the depressing means, means for moving the 120 said stripping means inward over the top edges of the box when they pass below said stripping means, means for arresting the motion of the depressing means when the stripping means are over the top edges of the box and means for moving the depressing means upward out of the box after the stripping means have moved over the top edges of the box, substantially as specified.
20. In a box covering machine the combination with a vertically movable box and cover support, and means for yieldingly resisting its downward movement, of mechanism for applying and affixing the sides and ends of the cover to the sides and ends of the box, a vertically movable plunger for holding the box and cover on the support and carrier and depressing the latter; a cam having a series of high and low points which are adapted to move the plunger downward rapidly at the beginning of the operation of the machine and while passing the side covering rollers, to arrest its motion when the tab folders are tucking in and affixing the tabs or projections of the sides against and affixing them to the ends of the box, to accelerate its motion while passing the rollers that turn up and affix the ends of the cover to the ends of the box and the infolded tabs or projections, to arrest its motion when the horizontally moving edge-turners are turning the edges of the cover over the top edges of the sides 135 and ends of the box, to move it upward to allow the support to be lifted and retain the box and cover between it and the plunger for the purpose of moving the horizontally turned over edges of the cover against the edge turners and cause them to turn the edges downward 140 parallel to the inside surfaces of the sides and ends of the box, and to hold it stationary while the turned down edges are affixed to the inside of the box, to again move it downward to carry the covered box to the strippers which strips the box from the plunger, and finally move it 145
- 150
- 155
- 160

upward to withdraw it from the box and return it to its normal position, substantially as specified.

21. In box covering machines the combination of edge turners, jaws for carrying the same, adjustable plates connected with said jaws, head blocks in which said plates are fastened, radially slidable plates that carry said head blocks, movable jaws hung on the plates that carry the edge turners jaws, clamps connected with movable jaws, rock levers fulcrumed on pins in the edge turner plates 10 and pivoted to the movable jaws, bell crank levers fulcrumed to the edge turner plates, rods that connect the arms of the bell crank levers with the rock levers which are pivoted to the movable jaws, springs that connect the bell crank levers with the edge turner plate, rock levers 15 fulcrumed on the slides that carry the head blocks, vertical rods connecting said rock levers with the arms of the bell crank levers, and means for operating said rock levers to cause the movable jaws to carry the clamps against the sides and ends of the box and clamp the same 20 with the interposed edges of the cover against the side of the edge turners and affix said edges to the inside of the box, substantially as specified.
22. In box covering machines the combination with box covering mechanism of a vertically movable plunger, a box 25 and cover support the movement of which is controlled by the plunger and that coacts with the plunger to carry and present the box and cover to the covering mechanism, a rod connected at its upper end with the box support, a piston carried by the lower end of said rod, an air cylinder in which said piston operates, a valve connected with 30 said cylinder, and means for opening and closing said valve to regulate the admission and compression of the air in the cylinder as the support is moved downward by the plunger, substantially as specified.
35. 23. In box covering machines means for applying the sides of the cover to the sides of the box, means for tucking in the tabs and fastening them to the ends of the box, means for applying the ends of the cover to the ends of the box, means for turning the edges of the cover over the 40 top edges of the box, means for turning the edges down inside the box, a vertically movable plunger, a vertically movable box and cover support that coacts with the said plunger to carry the box and cover and present them successively to the said covering means, a rod connected 45 at its upper end with the box and cover support and at its lower end with a piston, a weight connected with the piston, an air cylinder in which said piston operates and compresses the air when the piston is moved downward by the depression of the support to the edge turning means, a valve connected with the cylinder, means for closing the 50 valve when the support with the box and cover approaches the edge turning means and thus causes the piston to compress the air in the cylinder, means for moving the edge turners inward to turn the edges of the cover over the top edges of the box and pass within the lines of the sides and ends of the box, means for moving the plunger upward, means for moving the support upward with the plunger, substantially as specified.
60. 24. In box covering machines the combination of means for turning up and affixing the sides of the cover to the sides of the box, means for tucking in and affixing the tabs to the ends of the box, means for turning up and affixing the ends of the cover to the ends of the box, a vertically 65 movable plunger, a vertically and intermittently movable box and cover support which is depressed by the plunger and coacts therewith to carry the box and cover and present the same to the covering mechanism, a rod that connects at its upper end with the support and at its lower end with a piston, an air cylinder in which said piston operates, a valve connected with said cylinder, means for closing the 70 valve as the support descends to compress the air in the cylinder, means for moving the plunger down to carry the edges of the cover in line with the edge turners, means for arresting the downward movement of the 75 plunger when the edges of the cover are in line with the edge turners, means for moving the edge turners against the edges of the cover to cause the same to turn the edges horizontally over the edges of the box and to pass within the line of the sides and ends of the box and come together 80 end to end to form a frame, means for moving the plunger

upward after the edges of the cover are turned over, means for causing the support to move upward with the plunger to carry the edges of the cover against the bottom of the edge turners to cause the same to be turned parallel to the sides and ends of the box, means for overcoming the 85 inertia of the means by which the support is moved upward consisting in the pressure of the compressed air against the piston, means for arresting the upward motion of the plunger when the edges are turned down parallel to the sides of the edge turners and the sides and ends of the 90 box, means for clamping the sides and ends of the box and the interposed edges of the cover against the edge turners to affix the edges to the box, means for moving the plunger downward and means for opening the valve to let the air escape from the cylinder as the support descends, 95 substantially as specified.

25. In box covering machines means for applying the sides of the cover to the sides of the box, means for tucking in the tabs and fastening them to the ends of the box, means for applying the ends of the cover to the ends of the box, means for turning the edges of the cover over the top edges of the box, means for turning the edges down inside the box, a vertically and intermittently movable plunger, a vertically movable box and cover support that coacts with the said plunger to carry the box and cover and present them successively to the said covering means, a rod connected at its upper end with the support and at the lower end with a piston, a weight connected with the piston an air cylinder in which said piston operates and compresses the air when the piston is moved down by 100 the depression of the support to the edge turning means, a valve connected with the cylinder, means for closing the valve when the support with the box and cover approaches the edge turning means and thus causes the piston to compress the air in the cylinder, means for moving the 105 edge turners inward to turn the edges of the cover over the top edges of the box and pass within the lines of the sides and ends of the box, means for moving the plunger upward, means for moving the support upward with the plunger comprising the weight connected with the piston and the pressure of the compressed air against the piston to carry the edges of the cover against the edge turners to cause the latter to turn them down parallel to the sides and ends of the box, means for moving the plunger and support downward after the edges are affixed to the box, 110 and means for opening the valve to let the air escape as the piston descends, means for closing the valve when the piston reaches the bottom of the cylinder to hold the same by the suction and thereby hold the support down when the piston reaches its lowest position, substantially 115 as specified.

26. In a box covering machine the combination with box covering mechanism of a vertically movable plunger, a box and cover support the movement of which is controlled by the plunger and which coacts with the plunger to carry and present the box and cover to the covering mechanism, a rod connected at its upper end with the plunger, a piston carried by the lower end of the rod, a cylinder in which said piston operates, a valve connected with the cylinder, means for opening the same when the 120 plunger and support with the box and cover move downward over the edge turning mechanism, strippers, means for moving the same over the edges of the box after the plunger passes down to its lowest position, means for moving the plunger up after the strippers are moved over the edges of the box, means for closing the valve when the piston reaches its lowest position to prevent the entrance of air under the air and thereby cause the piston and support to be held down by suction while the plunger moves up out of the box and releases the support, substantially as specified.

27. In box covering machines means for applying the sides of the cover to the sides of the box, means for tucking in the tabs and fastening them to the ends of the box, means for applying the ends of the cover to the ends of the box, means for turning the edges of the cover over the top edges of the box, means for turning the edges down inside the box, a vertically movable plunger, a vertically movable box and cover support that coacts with the said plunger to carry the box and cover and present them successively to the 130

- the said covering means, a piston, an air cylinder in which said piston operates and compresses the air when the piston is moved downward by the depression of the support to the edge turning means, a rod connected at its lower 5 end with the piston and at its upper end with the box and cover support, a weight connected with the piston, a valve connected with the cylinder, means for closing the valve when the support with the box and cover approaches the edge turning means and thus causes the piston to compress the air in the cylinder, means for moving the edge turners inward to turn the edges of the cover over the top edges of the box and pass within the lines of the sides and ends of the box, means for moving the plunger upward, means for moving the support upward with the 10 plunger comprising the weight connected with the piston and the pressure of the compressed air against the piston to carry the edges of the cover against the edge turners to cause the latter to turn them down parallel to the sides and ends of the box, means for moving the plunger upward, means for opening the valve to let the air escape as the piston descends, means for closing the valve when the piston reaches the bottom of the cylinder to hold the same by suction and thereby hold the support down when 15 the piston reaches its lowest position, strippers located below the edge turning mechanism, means for moving the same over the top edges of the box when the plunger and support carry the box below the same, means for arresting the motion of the plunger when the box passes the strippers, means for moving the plunger upward out of the box and thus cause the strippers to strip the box off the same, means for moving the strippers away from the box to release the same, means for ejecting the box from the support, and means for gradually opening the valve to admit 20 the air slowly under the piston and thereby permit the support to return gradually to its normal position, substantially as specified.
28. In box covering machines the combination of a vertically movable plunger, a vertically movable box and cover support and carrier, horizontally movable edge-turners for turning the vertically projecting edges of the sides and ends of the cover over the top edges of the box and holding them in that position, means for moving the edge-turners and bringing them together end to end to form a pressure 25 supporting frame over and within the lines of the sides and ends of the box, and means for moving the support and carrier upward to carry the edges of the cover against the bottom of the edge carriers to cause them to turn the edges of the cover down parallel to the sides of the box, and means for arresting the upward movement of the plunger and support and carrier when the edges have been turned down, substantially as specified.
29. In box covering machines the combination of a vertically movable plunger, a vertically movable box and cover support, means for depressing the same, means for arresting the downward movement of the plunger and support, means for moving the edge turners inward within the vertical planes of the sides and ends of the box against the projecting edges of the cover for the purpose 30 of turning the edges of the cover to a horizontal position with respect to the top edges of the box, means for moving the plunger and support upward outside of the edge turners to cause the edge turners to turn the edges of the cover down parallel to the inside of the sides and ends of the box, means for arresting the upward movement of the plunger and support when the top edges of the cover are about in line horizontally with the bottom edges of the edge turners, and means for imparting pressure to the sides and ends of the box simultaneously and clamping them and the downturned edges of the cover against the sides of the edge turners and affixing them to the inside of the box, substantially as specified.
30. In box covering machines the combination of a feed table, floors below the feed table, a vertically movable plunger, a vertically movable box and cover support, means for applying and affixing the cover to the sides and ends of the box and turning the top edges over inside the box and affixing them thereto, strippers situated below the lowest floor adapted to move towards and over the edges 35 of the covered box when it reaches its lowest position and means for moving the plunger upward and out of the box while the box is held by the strippers on the support, and thus cause the strippers to strip the box from the plunger, substantially as specified.
31. In box covering machines the combination of a vertically movable plunger, a vertically movable box and cover support, means for applying and affixing the cover to the sides and ends of the box, edge turners for turning the top edges of the cover over and down inside of the box and affixing them thereto, means for stripping the covered box from the plunger, an ejector situated below the means for stripping the box from the plunger, means for driving the ejector against the box to eject it from the machine, substantially as specified. 85
32. In a box covering machine the combination of means for applying the cover to the sides and ends of the box, means for turning the edges of the cover over and affixing them to the sides and ends of the box, a plunger, a support for the box and cover connected to the upper end of a rod between which support and said plunger the box and cover are held, a cam for moving the plunger up and down and to cause it when traveling down to bear upon the box and cover and depress the support and thereby carry and present the box and cover to the covering and edge turning mechanism, means for moving the support yielding upward against the plunger, a piston connected with the lower end of the support rod, a cylinder in which said piston operates and compresses the air in the cylinder, means for arresting the downward movement of the plunger and support when the top edges of the box are in about the same horizontal plane as the bottom edges of the edge-turners and a relief valve for regulating the compression of air in the cylinder, substantially as specified. 90
33. In a box covering machine the combination of mechanism for applying the cover to the sides and ends of the box mechanism for turning the edges of the cover over and affixing them to the inside of the sides and ends of the box, a plunger, a support between which and the plunger the box and cover are held, said support connected with the upper end of a rod, a cam for moving the plunger up and down and to cause it when traveling down to bear upon the box and cover and depress the support and thereby carry and present the box and cover to the covering and edge covering mechanism, means for moving the support yielding upward against the plunger, a piston connected with the lower end of the support rod, a counter-weight connected with said piston, a cylinder in which said piston operates and compresses the air in the cylinder, a valve, and means for opening and closing the same to regulate the compression of air in the cylinder, means for arresting the downward movement of the plunger and support when the top edges of the box are in about the same horizontal plane as the bottom edges of the edge-turners, means for positively lifting the plunger to allow the support to move upward and carry the turned edges against the bottom of the edge turners to cause the latter to turn the edges down parallel to the sides and ends of the box, the upward movement of the support being produced by the compressed air in the cylinder acting against the piston and the gravitation of the weight connected with the piston, substantially as specified. 100
34. In a box covering machine the combination of mechanism for applying the cover to the sides and ends of the box mechanism for turning the edges of the cover over and affixing them to the inside of the sides and ends of the box, a plunger, a support for the box and cover, connected to the upper end of a rod between which support and said plunger the box and cover are held, a cam for moving the plunger up and down and to cause it when traveling down to bear upon the box and cover and depress the support and thereby carry and present the box and cover to the covering and edge-turning mechanism, means for moving the support yielding upward against the plunger, a piston connected with the lower end of the support a counter-weight connected with said piston, a cylinder in which said piston operates and compresses the air in the cylinder, a valve, and means for opening and closing the same to regulate the compression of the air in the cylinder, means for arresting the downward movement of the plunger and support 105

- its lowest position for the purpose of keeping the piston down by suction and thereby hold the support stationary until the covered box is ejected from the machine, a cam for partly opening the valve to admit air to the cylinder 5 under the piston and thereby reduce the suction and allow the support to move upward slowly, and a cam that allows the valve to close partly to reduce the influx of air under the piston, thereby increasing the suction and slowing the upward movement of the support, and then gradually opening the valve to increase the influx of air and by reducing the suction, cause the support to move upward with increasing speed until just before reaching its normal position the cam releases the valve which closes and thus stops the support in its normal position without shock or jar, 15 substantially as specified.
38. In box covering machines edge turners consisting of plates having their ends formed with jogs and chamfers means for bringing said plates together radially to form a rectangular side and end supporting frame for the inside 20 of the box, substantially as specified.
39. In box covering machines edge turners consisting of plates having their ends formed with jogs and chamfers to adapt them to form flush joints at the corners when brought together to form the side and end supporting 25 frame for the inside of the box and having their undersides hollowed out around the jogs, substantially as specified.
40. In a box covering machine the combination of edge turners, fixed jaws carrying the same, plates supporting the said jaws, means for moving the said plates in and 30 out radially, presser blocks, movable jaws hung on the plates that carry the fixed jaws, means for moving the movable jaws towards the fixed jaws and cause the presser blocks to clamp the top of the box and the down turned edges of the cover against the frame formed by the edge turners, substantially as specified.
41. In a box covering machine in combination a frame and a series of horizontal floors arranged in the frame forming successive super-imposed galleries, mechanism arranged in said galleries for covering the box, mechanism 35 for stripping the box from the covering mechanism, and mechanism for ejecting the covered box from the machine.
42. In a box covering machine in combination a frame, a series of horizontal floors arranged in said frame forming successive super-imposed galleries, mechanism arranged in said galleries for covering the sides of the box, mechanism 40 for tucking in the tabs, mechanism for turning up the end covers, mechanism for turning over the projecting edges of the cover and fastening them to the inside of the box, mechanism for stripping the box from the covering mechanism and mechanism for ejecting the box.
43. In a box covering machine in combination, a series of horizontal floors arranged in the frame of the machine forming successive super-imposed galleries, means in the 45 first gallery for covering the sides of the box, tucking in the end tabs, and covering the ends of the box, means in the second gallery for turning in the vertically projecting edges of the cover and affixing them to the inside of the box, means in the third gallery for stripping the box 50 from the covering mechanism and ejecting the box.
44. In a box covering machine in combination a series of horizontal floors arranged in the frame of the machine forming successive super-imposed galleries, driving mechanism to operate the mechanism which covers the box, strips and ejects it from the machine, mechanism for covering the sides of the box, turning in the end tabs, covering the ends, turning over the vertically projecting edges of the cover and fastening them to the inside of the box, mechanism for stripping the box from the mechanism which covers it, mechanism for ejecting the box from the machine, means for connecting the mechanism which covers the box, strips and ejects the box, with the driving mechanism in horizontal planes. 55
45. In a box covering machine in combination, a series of horizontal floors arranged in the frame of the machine forming successive super-imposed galleries, covering mechanism, tab folding mechanism, edge turning mechanism, stripping mechanism and ejecting mechanism arranged in the several galleries and means for operating the mechanism in each gallery separate and distinct from the mechanism which operates the mechanism in the other galleries. 60
46. In a box covering machine in combination, a series of horizontal floors in the frame forming successive super-imposed galleries, mechanism arranged in said galleries for covering the box, tab folding mechanism, edge turning mechanism, stripping mechanism, ejecting mechanism, a single driving shaft, with means for operating the mechanism in each gallery from said driving shaft. 65
47. In a box covering machine in combination, a series of horizontal floors in the frame forming successive super-imposed galleries, means in said galleries for turning up and affixing the sides of the cover to the sides of the box, means for tucking in and affixing the tabs to the ends of the box, means for turning up and affixing the ends of the cover to the ends of the box, means for turning the 90 vertically projecting edges of the box cover and affixing them to the inside of the box, stripping mechanism, ejecting mechanism, a vertically movable plunger and a vertically and intermittently movable box and cover support which is depressed by the plunger and coacts with said plunger to carry the box and cover through the successive galleries and present the box and cover to the side covering mechanism to the tab tucking mechanism, to the end covering mechanism to the edge turning mechanism, to the stripping mechanism and to the ejecting mechanism. 95
48. In a box covering machine in combination, a series of floors in the frame of the machine forming successive super-imposed galleries, means in the first gallery for covering the sides of the box, for tucking in the tabs, covering the ends of the box, vertically supporting plates to support the sides of the box while the end cover mechanism is applying the end covers to the ends of the box. 100
